UNITED STATES PATENT OFFICE.

HENRY LEMMON, OF GUELPH, ONTARIO, CANADA.

COMBINATION-LOCK.

SPECIFICATION forming part of Letters Patent No. 280,488, dated July 3, 1883.

Application filed April 10, 1882. (Model.)

To all whom it may concern:

Be it known that I, HENRY LEMMON, of the city of Guelph, in the county of Wellington, in the Province of Ontario, Dominion of Canada, watch-maker, have invented certain new and useful Attachments to Safe Combination-Locks; and I do hereby declare that the following is a full, clear, and exact description of the construction and operation of the same.

10 The great objection to safe combination-locks as at present used is that they can easily be opened, as has been done very successfully of late. For instance, the dial and lock are directly connected together by a spindle or shaft, which passes from the dial through the lock, which is opened by turning the said dial according as it is set. Burglars have opened safe-locks by driving in the spindle of the dial or pulling it out, then tapping the lock, and the bolt of 15 the lock would fall out and the safe be easily opened.

15 My invention relates to certain devices used with combination-locks in such a manner that safes are more secure and cannot be opened or tampered with.

20 The first part of my invention consists in removing the lock from the dial-spindle, placing a gear-wheel on the inner end of the said spindle, another one of similar size on the shaft of the 25 operating mechanism of the lock, and an intermediate gear-wheel meshing into both, by which means the lock is placed some distance away from the dial-spindle, unknown to a burglar, so that he would not know where to 30 drill for it to blast it.

35 The second part of my invention consists in a metal safety stop-plate fastened to the locking-bolts, its rear end being small and made to enter the bolt-hole of the combination-lock 40 when it is unlocked. The said plate is provided with two ratchet-wheels, one above the plate and one below it, and provided with pawls that have mechanism connected to them that cause them to operate automatically, the 45 object of the said automatic stop-plate being to act as a safety-guard to the lock in the event of the lock being tampered with. If the lock is broken by a burglar, the safe-door cannot be 50 opened.

55 By reference to the drawings forming part of this specification, Figure 1 is a plan view of a safe-door, showing the bolts thrown or locked. Fig. 2 is a side view of the same.

Fig. 3 is a plan view, showing the same unlocked and bolts drawn back. Fig. 4 is a plan 55 of the safe-door similar to Fig. 1, only it shows the automatic mechanism on the under side of the safety-plate and safe locked. Fig. 5 is a similar view to Fig. 3, showing the same automatic mechanism on the under side of the 60 safety-plate and safe unlocked. Fig. 6 is a front elevation of the lock. Figs. 7 and 8 are enlarged views of the automatic mechanism.

A represents the outlines of a combination-lock affixed to the inside of a safe-door, A'.

b is the bolt of the lock, the front edge of which is seen at Figs. 1, 2, 4, and 8, and when it is in that position the door is locked.

B, Fig. 2, is the dial, numbered on the outside face in the usual manner common to such 70 locks.

B' is the dial-spindle, passing from the register to the inside of the door A', and terminating in a cog-wheel, a, keyed to it, as shown more clearly at Fig. 2. c is a similar cog-wheel, keyed to the outer end of the spindle, which projects from the operating mechanism of the lock, and on a plane with the gear-wheel a; and b is an intermediate gear-wheel, of the 75 same size and kind as the others, affixed half-way between the two first named, on a spindle, e, attached to the inner side of the safe-door, as shown at Fig. 2. The said wheels all mesh into each other, are operated by the handle of dial B, and are for the purpose of effecting 80 communication between the dial B and lock A when the lock is removed from the said spindle a distance from it. The removal of the lock from the dial-spindle is to preserve the lock intact should the register-spindle be 85 driven in or pulled out by a burglar in attempting to force the lock to open the safe. I have shown gear-wheels meshing into each other to form this connection between the dial and lock; but a crank or equivalent device placed 90 on the said spindle and connecting with the lock would answer the same purpose. The lock is opened in the usual manner by turning the dial B in accordance with the combination-figures to which it has previously been set.

95 f is a nut on the spindle B', which is screw-threaded at that part to prevent the said spindle from being pulled out.

100 C C are the locking-bolts, which pass through holes in the projecting pieces C' C'.

105 D is a metal plate affixed to the locking-

bolts C C. It is of different widths. Its small end 2 is made to enter the lock when it is open, and impinge on the bolt b of the lock A when it is closed or locked. The spindle g of the handle h passes through the said plate D, going through a slot, L, cut in the said plate. Said slot allows the plate D to be pushed back and forth in opening and closing the safe-door. It will be observed that when the bolt b of the lock is down or locked, as in Fig. 1, where it shows the end of it, the end of the plate D cannot be pushed back into the lock. Consequently the bolts C cannot come back, as they are secured to the plate, and the said Figs. 1 and 2 show the position of all the parts when the safe is locked. When the safe-door is locked, I do not wish the handle h to be used as a means of force by a burglar against the lock by using powerful instruments on the handle 20 to press against the bolt b of the lock. Consequently I construct automatic mechanism under the said plate D, which is operated by the bolt b of the lock. When it closes or is locked, the handle-spindle g is disengaged from the plate D and turns loosely in the door. The means by which this is accomplished is seen at Figs. 4 and 5, and it will be observed that I have reversed the plate D, or turned its underside outward in both of said figures to show 30 the parts more plainly.

Reference to Fig. 1 shows a ratchet-wheel, K, on the spindle g of the handle h on the top of the plate D. A pawl, i, is pivoted to the said plate D to engage with the said ratchet-wheel at the proper time to throw back the plate D and bolts C, as will be more fully explained hereinafter. A small spring, j, is secured at one end to the bolt-frame C. Its forward end comes in contact with the pawl i, and it is for the purpose of throwing the pawl off the wheel when it is not required there.

On the under side of the plate D, immediately under the said ratchet K, is a similar ratchet-wheel, E, keyed on the spindle g, and a pawl, H, secured a short distance from it, to engage with it. Fig. 4 shows it disengaged with the ratchet when the bolts are locked and the handle h turns loosely, and Fig. 5 shows the same pawl engaged with the said ratchet-wheel when the safe is unlocked. The means of automatically operating this said pawl H is as follows: One end of a connecting-rod, I, is attached to it, Figs. 4, 5, and 7, which rod passes obliquely down between two small pulleys, k l, attached in boxes to the plate D, and terminates in a small friction-wheel, m, at its opposite end, which impinges on the flat slanting end of a swiveled dog, J, which is loosely pivoted to the rear or small part, 2, of the plate D. (See Fig. 4.) The lower end of the said connecting-rod I is screw-threaded, and has a socket, n, screwed on it, so that the said rod can be nicely adjusted by being lengthened or shortened, in order to have the proper 65 length to be operated upon by the dog J and throw the pawl on or off the ratchet-wheel E.

It will be observed that the operation of the

above parts are as follows: When the safe is locked, for instance, the bolt b of the lock presses against the outer end of the dog J, the flat slanting portion o of which impinges against the friction-wheel m of the connecting-rod I and pushes the pawl H off the ratchet-wheel E, so that the spindle g and both ratchet-wheels will turn loosely with the movement of the handle h and not operate or move the plate D, to which the locking-bolts are affixed.

When the safe is unlocked, by turning the dial B to the set numbers the bolt b of the lock A is withdrawn or rolls back, the part o of the dog J, being heavier than the other half of it, drops a little and allows the pawl H to fall against and engage with the teeth of the ratchet-wheel, as shown at Fig. 5, when by turning the handle backward the end of the plate D 85 enters the open bolt-hole of the lock and allows the locking-bolts C C to be withdrawn and the safe-door to open.

By reference to Fig. 3 it will be seen that when the rear end of the plate D enters the lock A and the safe is open the top pawl, i, is released from the spring j and falls into and engages with the top ratchet-wheel, K. In order, then, to lock the door of the safe, by turning the handle h to the left the plate D 95 can be moved back again, and with it the locking-bolts C C shot in their places. The dial is turned, and the bolt b of the combination-lock falls and closes the bolt-opening opposite the rear end, 2, of the plate D. The falling of the 100 said bolt b against the dog J releases the pawl H from the under ratchet-wheel, and the spring j on the upper side of the plate D comes in contact with the upper pawl, i, and releases it from the upper ratchet-wheel, K, and thus allows the spindle g of the handle h to turn loosely and not interfere with the other parts.

When the safe is locked, it will be found impossible to open it, except by turning the dial to the proper combination of figures to 110 which the lock has been set.

Having thus described my device, what I claim as my invention is—

1. In combination with the lock A and plate D, the mechanism to operate the plate D and locking-bolts C C, consisting of the ratchet-wheel K on the spindle g, pawl i, and spring j on the upper part of the plate D, substantially as and for the purpose specified.

2. The combination, with the lock A and plate D, of the ratchet-wheel E, pawl H, connecting-rod I, pulleys k l, friction-wheel o, and dog J, substantially as and for the purpose specified.

3. In a permutation-lock, the combination, with the pawl H and dog J, of the rod I and screw-socket n, containing the friction-wheel m, to adjust the length of said rod, as specified.

Guelph, Ontario, Canada, March 7, 1882.

HENRY LEMMON.

In presence of—

JOHN HUTTON,

WILLIAM FARRAR.
